CLAIM

The ornamental design for a grill pan, as shown and described.

DESCRIPTION

FIG. 1 is a perspective view of a grill pan;
FIG. 2 is a front view of the grill pan, the rear view being the
mirror image thereof; and,
FIG. 3 is a right side view of the grill pan, the left side view
being the mirror image thereof.

1 Claim, 2 Drawing Sheets

FIG. 1

FIG. 2

FIG. 3
